UNITED STATES PATENT OFFICE.

ALBERT H. EHRLICH, OF ST. JOSEPH, MISSOURI.

REFRIGERATOR DISPLAY COUNTER.

Application filed May 4, 1921. Serial No. 466,801.

To all whom it may concern:

Be it known that I, ALBERT H. EHRLICH, residing at St. Joseph, in the county of Buchanan and State of Missouri, a citizen of 5
the United States, have invented certain new and useful Improvements in Refrigerator Display Counters, of which the following is a specification.

This invention relates to refrigerators, and 10 more particularly to refrigerator display counters, and has for its object the arrangement of the display compartment and the storage compartments with relation to the cooling pipes therefor, the object being to 15 arrange the display compartment so that there is a clear and unobstructed view of the contents thereof.

A further object is to arrange the cooling pipes for the display compartment at the 20 rear thereof and out of the way of the sliding doors, which permit access to the display compartment.

In the accompanying drawings:

Fig. 1 is a perspective view of the display counter complete;

Fig. 2 is a transverse sectional view through the upper display compartment and rear shelf;

Fig. 3 is a detail perspective view of one 30 of the metal brackets.

The numeral 1 indicates the upper portion or compartment of the refrigerator, which is entirely enclosed, except the doors at the rear. The upper compartment preferably 35 consists of a marble slab 2 as a base, which is placed on the top of the lower compartment, being less in width, however, than the width of the lower compartment.

The numeral 3 indicates a plurality of inverted L-shaped metal brackets, which are attached to the front edge of the top of the lower compartment, embracing the slab 2, being detachably secured to the lower compartment by clamps 4. These brackets serve 45 as a support for the front, top and end glass or other transparent panels 5, 6 and 7 respectively.

Interposed between the marble top and the lower edges of the transparent panels, 50 I preferably insert the groove-shaped rubber gasket or packing 8 to insure a tight fit to hold in the cold air.

The rear ends of the brackets are connected together by a longitudinally arranged strip 8' which extends the full length of the 55 counter.

The numeral 9 indicates a shelf arranged in the rear of the display compartment, being elevated from the base of the display compartment and supported on suitable 60 metal brackets 9', forming an opening 10 at the rear of the display compartment which communicates with the lower storage compartments. Arranged within this opening 10 are cooling-pipes 11 connected with similar cooling-pipes arranged as desired in the lower storage compartments. A plurality of sliding-doors 12 are arranged at the rear of the display compartment being received between the shelf and the longitudinal strip 70 8', the lower surface of which is provided with grooves 13 to receive the tongue edge of the sliding-doors, the tongues projecting from the upper edge of the sliding door, while the bottoms of the doors (as at 14) 75 rest upon the shelf adapted to slide upon suitable roller-bearings 15. These doors are preferably divided into pairs and adapted to slide by one another, whereby access may be had to any particular part of the transparent compartment without unnecessarily having a large opening at the rear.

It will thus be seen that I have constructed and arranged a display refrigerator counter which, while providing ample space 85 for storage purposes below, affords an ample display space above to exhibit the articles for sale, and means for keeping the articles that are on display in good condition, so that they are not only pleasing to the eye 90 but are palatable.

I claim:

A refrigerator show-case including a counter, a detachable glass enclosed case extending along the top thereof and clamped thereto, the said case having a compartment along the rear portion thereof and opening into the said case, the top of said compartment being formed as a shelf, cooling pipes in said shelf compartment, and doors between the said shelf and the upper rear edge of said case.

In testimony whereof I hereunto affix my signature.

ALBERT H. EHRLICH.
